UNITED STATES PATENT OFFICE.

WILLIAM STANLEY, JR., OF PITTSBURG, PENNSYLVANIA.

ARMATURE FOR DYNAMO-ELECTRIC MACHINES.

SPECIFICATION forming part of Letters Patent No. 313,894, dated March 17, 1885.

Application filed September 23, 1884. (No model.)

To all whom it may concern:

Be it known that I, WILLIAM STANLEY, Jr., a citizen of the United States, residing in the city of Pittsburg, in the State of Pennsylvania, have invented certain new and useful Improvements in Armatures for Dynamo-Electric Machines, of which the following is a specification.

My invention relates especially to that class of armatures known as "drum" armatures, in which the wires are wound longitudinally upon the surface of a revolving drum or core; and the object of my improvements is to provide a core for such armatures which can be easily and cheaply constructed and shall be free from the so-called "Foucault currents." Heretofore such armature-cores have generally been constructed of a number of separate plates of iron arranged side by side with layers of insulating material interposed between them, in order to prevent the production of currents in the core itself. Such armature-cores are difficult to make, and add greatly to the cost of the machine.

In constructing my armature I avoid the use of separate plates and dispense with insulating material by making an armature-core of a series of parallel disks and shaft-bearings and bars connecting the same, cast of iron in one piece. The cost of such an armature-core is but a small fraction of that of one constructed in the ordinary manner, while it is free from induced Foucault currents, and consequent heating of the iron and loss of energy.

In the drawings, Figure 1 shows a side elevation of the armature-core; Fig. 2, a longitudinal section, and Figs. 3 and 4 cross-sectional views.

A A are the end plates; a a a, intermediate plates or disks; B B B, bars connecting the plates, and C C perforations in the end plates, A A.

The same letters refer to similar parts in all the drawings.

As appears from the drawings, my armature-cores are constructed in the form of a series of perforated disks a, parallel to each other and at right angles to the axis of the armature. These rings are separated from each other by a short distance, so as to insulate them from each other at their outer circum-

ference and afford a free circulation of air between them. Through the center of each of the disks a is a large opening, so that the armature-core is hollow throughout its length 55 between the end plates, A A. The end plates, A A, are made thicker than the intermediate disks a, and are provided with projections D D, fitted to receive the shaft of the armature, which is keyed in the slot d. The end plates, 60 A A, are pierced with openings C, which, in connection with the opening through the center of the core and the spaces between the disks a, permit a current of air to circulate freely throughout the armature, so as to cool 65 it and prevent heating of the metal during the operation of the machine. Along the inner edge of the perforated disks a run the bars B, connecting the disks a and the end plates, A A, and uniting the whole into one piece. The 70 bars B should be made of sufficient size to prevent any bending or warping of the armature, but should not extend up very far toward the outer circumference of the disks a.

It is well known that if a hollow cylinder 75 be magnetized the whole charge will appear on its outer surface, while none can be detected on its inner surface.

Any Foucault currents that may be generated in my armature-core during the operation 80 of the dynamo are confined to the outer circumference of the disks a, and the space which such currents can traverse is measured by the thickness of each disk. The currents are prevented from passing from disk to disk by the 85 insulating bodies of air between the disks, and as the connecting-bars B are placed at the inner circumference of the perforated disks the currents that may be generated on the outer circumference do not extend to the connect- 90 ing-bars.

I am aware that the armature-cores of dynamo-electric machines have heretofore been made of flat disks parallel to each other and at right angles to the axis of the armature, 95 and also that cast-iron has been used as a material in their construction, and I do not claim either of these, broadly.

What I do claim as new, and desire to secure by Letters Patent, is—

1. An armature-core consisting of the end plates, A, disks a, and bars B, the whole cast

of iron in a single piece, substantially as described.

2. The combination, in an armature-core, of end plates, A, perforated disks *a*, and bars B along the inner circumference of the disks, rigidly uniting the disks and end plates into a single piece, substantially as described, and for the purposes set forth.

3. An armature-core consisting of a series of annular disks composed of a single piece of cast-iron, substantially as shown and described.

WILLIAM STANLEY, JR.
